PUSHER RAM FOR COKE OVENS

Heinrich Koppers, Essen, Germany; vested in
the Alien Property Custodian

Application January 6, 1941, Serial No. 373,295
In Germany December 12, 1939

8 Claims. (CL 214—23)

The present invention relates to devices for the removal of the coke cake from the coking chambers or retorts of horizontal chamber- or retort-ovens for the production of gas and coke, and more particularly to devices for the purpose set forth above which comprise a pusher ram which is connected with means for effecting a reciprocating movement thereof.

It is common usage to equip a horizontal chamber oven battery with a pusher ram for pushing the incandescent coke cakes out of the oven chambers, said pusher ram comprising a pusher head or shield which is supported by an essentially horizontal pusher bar or rod. The dimensions of the pusher head are a little bit smaller than those of the oven chambers so that the pusher head may be easily moved to and fro inside the chambers. When the carbonization of the coal charge in the chamber is finished, the doors at both sides of the chamber are opened and the pusher ram is introduced into the chamber from one side. The coke cake formed in the chamber is thereby pushed out at the other side of the chamber. In so pushing the chambers, the pusher ram moves forwardly through the whole chamber to be emptied and is then drawn back through the same, after the chamber is completely discharged, to remove the pusher head from the chamber.

During the pushing procedure, the pusher ram or rod is exposed to the high temperature of the coking chamber, the walls of which mostly have a temperature exceeding 1000° C. When the pusher ram is drawn back out of the chamber after the discharge is completed, it cools down rather quickly. This frequent heating up and cooling down of the pusher ram has a detrimental effect on its metal body.

The main object of my invention, therefore, is to provide such improvements in the pusher rams as will protect the rod against the influence of the high temperatures in the coking chambers and increase its stability to a considerable extent.

It is usual to design the pusher ram of coke ovens in the form of an I-beam having a central web portion and two flanges, the central web of which extends vertically. This design, I too principally adopted for my invention.

For the reciprocating movement of the pusher ram, there is generally applied a spur rack fitted to the pusher rod and a pinion connected with a suitable drive is geared to this spur rack. When the pinion turns in one direction, the pusher ram is moved into the chamber, and the

ram is withdrawn from the chamber on the opposite movement of the pinion. I, likewise, retain this driving mechanism for the pusher ram.

My invention now provides for arranging said spur rack for the pinion at one side of the vertically disposed central web and to fit protection plates, preferably consisting of thick-walled cast iron plates, to the other side of the central web. By this arrangement, the relatively thin central web of the pusher ram, which was susceptible to radiation, is protected against the disadvantageous heat radiation of the highly heated chamber walls in a very simple though effective manner.

Preferably, I use an I-beam, the central web of which is of less height than the width of the flanges which extend crosswise of the web.

With the above and other objects and features of my present invention in view, I shall now describe a preferred embodiment thereof on the lines of the accompanying drawing in which

Fig. 1 shows a vertical section through the pusher ram with its driving mechanism,

Fig. 2 represents a side elevational view of the pushing ram, and

Fig. 3 is a sectional view of a modified form of the invention.

The pusher ram 1 consists of a wide-flanged I-beam as, for instance, the German industrial standard 30. In such wide-flanged I-beams, the horizontal flanges 2 have a thickness of 20 mm., while the vertical web 3 has a thickness of only 12 mm. On one side of the vertical web 3, a spur rack 4 is fixed. The other side of the vertical web 3 is fitted with protection plates 5, preferably consisting of cast iron.

The spur rack 4 is geared to a pinion 6, which is seated for rotation in a horizontal plane around a vertical axis in a supporting frame 7. The latter is equipped with a connecting arm 8 which serves as a support for the shaft bearing 9 above the pinion 6. Above the bearing 9, a pinion 11 is provided, which is to be connected to a driving means therefor that is coupled to a driving motor (not shown).

In order to take up the counterpressure of the driving pinion on the pusher web 3, a wheel 12, arranged in a supporting seat 13, is provided at that side of the web 3, to which is fitted the protection plates 5. The wheel 12 is guided in the guide bearing 14 by means of a vertical shaft, the guide bearing 14 being connected at 15 with the bearing 10 of the connecting arm 8. The connection 15 is preferably adjustable so that with a corresponding adjustment of the supporting

seat 13, which is designed for adjustment accordingly, an adjustment of the wheel 12 may be attained to assure that the wheel 12 lies closely against the pusher web 3 even if some wear and tear may occur during the operation of the ram 1. The pusher ram 1 is guided within the usual pushing machine by means of the lower carrying rolls 16 and the upper guide rolls 17, in order to render a tilting movement of the ram 4 towards the top of the machine impossible.

Instead of having the cast iron protection plates 5 and the counterpressure wheels 12 on one side of the vertical rod 3, another spur rack 4a, which is geared to a toothed wheel 6a, may be provided, whereby the pressure of the driving pinion 6 is taken up, and a banding of the pusher web 3 in a lateral direction is safely avoided.

I have now described my present invention on the lines of a preferred embodiment thereof, but my invention is not limited in all its aspects to the mode of carrying it out as described and shown, since the invention may be variously embodied within the scope of the following claims, to make subsequent claims is hereby expressly reserved.

I claim:

1. A pusher ram for coking chambers comprising, a metallic beam having a vertical web portion and relatively thicker upper and lower transverse flange portions, protection plates affixed to the web portion and substantially covering the opposite web faces, and a toothed rack formed on one of said protection plates for mechanical reciprocation of the ram into and out of the coking chamber.

2. A pusher ram for coking chambers comprising, a steel beam having a vertical web portion and relatively thicker upper and lower transverse flange portions, a cast iron protection plate affixed to the web portion and substantially covering one of the web faces, and a toothed rack formed on said plate for mechanical reciprocation of the ram into and out of the coking chamber.

3. A pusher ram for coking chambers comprising, a metallic I-beam having a vertical web portion and relatively thicker upper and lower

transverse flange portions, a toothed rack affixed to one vertical face of the I-beam web portion for mechanical reciprocation of the ram into and out of the coking chamber, and a protection plate affixed to and substantially covering the opposite face of the web portion.

4. Apparatus as claimed in claim 2 and which includes a pinion rotatably engaging the rack, a vertically disposed drive shaft for said pinion, 10 a second vertically disposed shaft and a counter-pressure wheel on said second shaft for engaging the opposite face of said web from said plate.

5. Apparatus as claimed in claim 2 and which includes a pinion rotatably engaging the rack, a drive shaft for said pinion, a second shaft parallel to said first shaft, a counterpressure wheel on said second shaft for engaging the opposite face of said ram from said pinion, a pair of fixed bearings for one end of said first and second shafts, 15 a second pair of bearings for the other ends of said shafts, and an adjustable connection between said second bearings.

6. Apparatus as claimed in claim 2 and which includes a driven pinion rotatably meshing with the rack, and rotatable counterpressure means 20 mounted for rotation alongside the opposite vertical side of the web portion, opposite the driven pinion, to exert counterpressure on the web portion along its vertical side opposite the driven pinion.

7. Apparatus as claimed in claim 1 and which includes a driven pinion rotatably meshing with the rack, and rotatable counterpressure means 25 mounted for rotation alongside the protection plate opposite the driven pinion, to exert counterpressure on the web portion along its vertical side opposite the driven pinion.

8. A pusher ram for coking chambers comprising, a metallic beam having a vertical web portion and relatively thicker upper and lower transverse flange portions, protection plates affixed to the web portion and substantially covering the opposite web faces, and a toothed rack formed on each of said protection plates for mechanical reciprocation of the ram into and out of the coking 30 chambers.

HEINRICH KOPPERS.
